UNITED STATES PATENT OFFICE.

JAMES R. GRAY, OF AYER, ASSIGNOR TO THE SAWYER SPINDLE COMPANY,
OF BOSTON, MASSACHUSETTS.

SPINDLE FOR RING-SPINNING FRAMES.

SPECIFICATION forming part of Letters Patent No. 288,230, dated November 13, 1883.

Application filed November 18, 1882. (No model.)

To all whom it may concern:

Be it known that I, JAMES R. GRAY, a citizen of the United States, residing at Ayer, in the county of Middlesex and State of Massachusetts, have invented a new and useful Improvement in Spindles for Ring-Spinning Frames; and I do hereby declare the following to be a full, clear, and exact description of the same, reference being had to the accompanying drawings.

My invention has for its object to provide a spindle that shall be entirely free from the evil effects due to the tension of the driving-band, and be able to yield with such freedom in all lateral directions when running that it may easily and without restraint assume any direction of rotation required to accommodate all variations in the distribution of its bobbin-load occurring in practical use.

It consists, essentially, in cutting the spindle into two separate parts, and then interposing between such parts an intermediate flexible connection adapted to impart rotation from the lower to the upper part, and at the same time allow the upper part to assume and maintain an independent axis of rotation with relation to the lower part, such upper part, which alone receives and supports the bobbin, being supported within the bolster by a yielding bushing, which allows it to move laterally throughout its entire length.

Referring to the accompanying drawings, Figure 1 is an external elevation of my improved spindle as applied to the usual bolster-rail of a spinning-frame; Fig. 2, a sectional elevation of the same, and Fig. 3 a plan or top view of the whirl-spindle *p*.

B is a bolster secured to the rail *R* by the nut-bracket *D*, which also carries the step or vertical support of the whirl-spindle *p*, the whirl-spindle taking its lateral support within the lower end of the bolster *B*, and being driven by the whirl *w*, which is preferably made to sleeve the lower end of the bolster, as shown.

The upper bobbin-carrying spindle, *A*, revolves within the steady-bushing *e*, which is loosely fitted within the bolster, and allows the spindle *A* to move laterally throughout its entire length, thus enabling the spindle to change the direction of its axis of rotation and accommodate itself to an unequally-distribut-

ed bobbin-load, or, in other words, to "center itself," upon the well-known principle of a child's top. In order that the spindle *A* may thus center itself, as described, and at the same time receive rotary motion from the whirl-spindle, the two are connected or locked together by means of the flexible connection *k*, which is preferably made from flat wire or sheet metal of such width that it will loosely fit within the bore *i*, formed in the butt of the spindle *A*, and of such a thickness that it will also loosely fit the slots *c*, Fig. 3, formed across the upper end of the whirl-spindle, and *c'*, formed across the plug *d*, which is driven into the bore *i*. To render the connection *k* more flexible in its operation, it is twisted spirally to a quarter-turn, bringing its two ends into vertical planes which are at right angles to each other, and the operation of the parts becomes similar to that of the well-known universal joint.

The slot *c'* may be located at or near the lower end of the spindle *A* and the bore *i* omitted; but by locating the slot as shown the parts are brought into a more compact form, and the connection *k* can be made longer, and consequently more flexible in its operation.

The steady-bushing *e* is loosely locked within the bolster by the retaining-screw *S*, which also acts, in conjunction with the shoulder *h*, to prevent the spindle from being raised when the bobbin is doffed.

Oil is supplied at the oil-trough *t* and passes through the educt *r* to the interior of the bolster.

Having thus described my invention, what I claim is—

1. The combination of the upper spindle, *A*, provided with the slotted plug *d* at or near its lower end, the lower spindle, *p*, having the slot *c* at its upper end, and the intermediate flexible connection *k*, loosely fitting the slots *c* and *c'*, and adapted to engage the same in vertical planes which are at right angles to each other, and allow the upper spindle, *A*, to change its axis of rotation in all lateral directions independently of the spindle *p*, substantially as described.

2. A lower whirl-spindle and an upper bobbin-carrying spindle, combined and connected

by means of a flexible connection interposed between said spindles, and adapted to impart rotary motion from the lower to the upper spindle, and at the same time allow the upper spindle to move laterally throughout its entire length, as set forth.

3. A lower whirl-spindle and an upper bobbin-carrying spindle, combined and connected by means of a connection interposed between said spindles, and adapted to impart rotary motion from the lower to the upper spindle,

and at the same time allow the upper spindle to move laterally throughout its entire length, as set forth.

In testimony whereof I have signed my name 15 to this specification in the presence of two subscribing witnesses.

JAMES R. GRAY.
